(No Model.)

G. CARLSON & P. LAWSON.
BARBER'S CASE.

No. 569,274.

Patented Oct. 13, 1896.

UNITED STATES PATENT OFFICE.

GUSTAVE CARLSON AND PERRY LAWSON, OF VALENTINE, NEBRASKA.

BARBER'S CASE.

SPECIFICATION forming part of Letters Patent No. 569,274, dated October 13, 1896.

Application filed June 4, 1896. Serial No. 594,333. (No model.)

To all whom it may concern:

Be it known that we, GUSTAVE CARLSON and PERRY LAWSON, citizens of the United States, residing at Valentine, in the county 5 of Cherry and State of Nebraska, have invented an Improvement in Barbers' Cases, of which the following is a specification.

This invention relates to barbers' cases, and the objects thereof are to provide an improved 10 box or casing for the reception of a barber's outfit, including razors, combs, straps, &c.; and with these and other objects in view the invention consists in the construction, combination, and arrangement of parts herein- 15 after described and claimed.

The invention is fully disclosed in the following specification, of which the accompanying drawings form a part, in which—

Figure 1 is a plan view of the box or casing 20 open; Fig. 2, an end view thereof closed; Fig. 3, a section on the line 3 3 of Fig. 1; Fig. 4, a section on the line 4 4 of Fig. 1; Fig. 5, a plan view of a detail of the construction; Fig. 6, a side view of a modified form of construction, and Fig. 7 an end view thereof.

In the practice of our invention we provide a box or casing which consists of two similar 25 parts A and B, which are preferably rectangular in form and hinged together at b. One 30 of these parts, the part B, as shown in the drawings, is provided with inclined raised portions b² in the bottom thereof, which are designed for holding or supporting combs and similar articles, a spring-clamp b³ being secured at the base of each for this purpose, and the other is provided with a plurality of transverse chambers a, which are formed by vertical 35 transverse partition-walls a², and each of the chambers a is provided with a cover a³, which 40 is hinged at one end thereof, as shown at a⁴, and on the hinge-pins D, which are employed for connecting the covers a³ with the partition- 45 walls a², are mounted springs d, one end of which is secured to the adjacent partition- 50 wall a² and the other to the cover, and the object of these springs is to hold the covers closed, and secured to the bottom of each of these covers are transverse strips E, of leather or similar material, between which and the 55 covers the razors are inserted. We also secure to the back of one of the parts A and B a supplemental casing G, in which is mounted

a razor-strap g, which is shown in dotted lines in Fig. 2, the end of which projects from the casing G, as shown at g², and the inner end 55 of said strap is provided with a cord or belt g³, which passes around a pulley g⁴ at the opposite end of the casing and around a pulley g⁵, which is secured to the end of the casing 60 opposite the pulley g⁴ by a spiral spring g⁶, and the end of the cord or belt G is carried 65 back and secured to the casing at g⁷, and by means of this construction the strap g may be withdrawn from the casing whenever desired for use, and when released it will be 70 drawn back into the casing by the spring g⁶, as will be readily understood.

As a modification of this construction we may employ a circular casing H, having a base h, by which it may be secured to the main box 70 or casing, composed of the parts A and B, and in one side of which is a transverse slot or opening h², and in which is mounted a spring drum or roller h⁴, on which the strap g is wound, and, as will be readily understood, the 75 strap g may be withdrawn by the end piece g² whenever desired, and when released it will be again rewound on the spring drum or roller h⁴.

It will thus be seen that we accomplish the 80 object of our invention by means of a device which is simple in construction and operation and perfectly adapted to accomplish the result for which it is intended, and the box or casing may be large enough to contain any 85 desired number of articles, including brushes, combs, razors, &c., and it is evident that changes therein and modifications thereof may be made without departing from the spirit of our invention or sacrificing its ad- 90 vantages.

Having fully described our invention, we claim as new and desire to secure by Letters Patent—

1. A box or casing of the class herein described, consisting of two separate similar parts which are hinged together, one of said parts being provided with inclined ledges or shelves, and spring-clamps for securing the combs or other articles thereto, and the other being provided with transverse chambers which are provided with straps for securing razors thereto, substantially as shown and described. 95 100

2. A box or casing of the class herein described, consisting of two separate similar parts which are hinged together, one of said parts being provided with inclined ledges or shelves, and spring-clamps for securing the combs or other articles thereto, and the other being provided with transverse chambers which are provided with straps for securing razors, thereto, said box or casing being also provided with a supplemental casing which is secured to the outer side thereof in which is mounted a razor-strap which is retained therein by a spring and which is adapted to

be withdrawn therefrom when required for use, and to return thereto by said spring, substantially as shown and described. 15

In testimony that we claim the foregoing as our invention we have signed our names, in presence of the subscribing witnesses, this 8th day of May, 1896.

GUSTAVE CARLSON.
PERRY LAWSON.

Witnesses:

JAMES ALBERT CARROLL,
JOHN T. KEELEY.
